UNITED STATES PATENT OFFICE.

RALPH G. JACKSON, OF CHESTER, PENNSYLVANIA, ASSIGNOR TO CONGOLEUM COMPANY, INCORPORATED, OF NEW YORK, N. Y., A CORPORATION OF NEW YORK.

MACHINE FOR SPLICING FELTS AND FABRICS.

Application filed February 1, 1921. Serial No. 441,592.

To all whom it may concern:

Be it known that I, RALPH G. JACKSON, a citizen of the United States, residing in Chester, Delaware County, Pennsylvania, have invented certain Improvements in Machines for Splicing Felts and Fabrics, of which the following is a specification.

My invention is especially adapted for splicing felt which has to be coated by being passed through a coating or saturating machine. In this type of machine, a roll of felt is passed therethrough until the end is reached, which end is secured to a piece of another roll, rendering it unnecessary to thread the new roll through the machine, as it is drawn through by the roll to which it is attached. The ends are preferably detached after they have passed through the machine so that each roll can be handled independently.

The object of my invention is to provide a machine by which pieces of felt can be secured together in a substantial and rapid manner.

In the accompany drawings:

Fig. 1 is a plan view of my improved machine for splicing felt and other fabrics;

Fig. 2 is an enlarged side view of the machine;

Fig. 3 is an end view;

Fig. 4 is a plan view; showing the thread placed on the several needles;

Fig. 5 is a sectional view on the line 5—5, Fig. 4;

Fig. 6 is a view showing the two pieces of fabric punctured by the needles with the threads projecting through the perforations and also showing the draw wires threading the several loops;

Fig. 7 is a sectional view on the line 7—7, Fig. 6;

Fig. 8 is a detached perspective view of one of the needles;

Fig. 9 is a perspective view of a portion of two pieces of felt and showing two sets of cords forming the splice; and

Fig. 10 is a perspective view of one of the draw wires.

Referring to the drawings, 1 is a frame supported on suitable legs 2. Carried by this frame are two beams 3 spaced apart to form a channel 4 extending from one end of the machine to the other. Mounted in the channel 4 is the needle carrier 5, shown

clearly in Fig. 5, and projecting from 55 this carrier are the two lines of needles 6, preferably of the type shown in Fig. 5, said needles being shaped to penetrate the felt and having a notch 8 to receive the transverse thread which is passed through the 60 loops when the needles, with their loops, are projected through the fabric, as in Fig. 7.

At the end of each needle is a groove 7 for the other thread, or cord, which is placed in the grooves, as shown clearly in 65 Fig. 4.

a is one sheet of felt and *b* is the other sheet of felt, which is secured to the sheet *a*. *c*, *c*, are the cords, which are formed into loops. *d*, *d* are the cords which pass 70 through the loops and which complete the stitches.

The needle carrier is raised and lowered by means of plungers, Fig. 2, each of which is connected to one arm of a bell crank lever 10, pivoted at 11 to the frame 1. The other arm of each bell crank lever is connected by a rod 12 to a lever 13 pivoted at 14 to a bracket on one of the legs 2. This lever 13 has a handle 15 by which the operator 75 moves the lever. On the frame is a plate and pivoted to the lever 13 is a toothed dog 17, which is arranged to engage the plate 16 and hold the lever in the position in which it is adjusted, the teeth of the dog 80 engaging the plate 16.

When it is wished to release the needle carrier and lower it, the dog is raised clear of the plate 16, when the weight of the needle carrier will cause it to drop to its 90 normal position. The needle carrier has projections 18 at each end resting against abutments 19 on the frame. Directly above the needle carrier is a bar 20. This bar has a series of perforations corresponding 95 with the needles so that the needles, when the needle carrier is raised, pass through the fabric and into the perforations of the bar. In the drawings, this bar is shown as made in two parts, or sections. This bar 100 is carried by the upper clamp members 21 located at each side of the machine. Extending from one clamp member to the other are metal bars 22. Clips 23 on the bar 20 engage the cross bars 22 and hold 105 the bar 20 in position so that it will move vertically with the clamping members 21. The bar 20 is held against longitudinal

movement by guides 24 mounted on brackets 25 secured to the frame 1. The beams 3 are permanently secured to the frame 1 and form the lower clamping members.

In order to raise and lower the upper clamping members 21, two shafts 26 are provided adapted to bearings on the beams 3. On these shafts are eccentrics 27 mounted in straps 28 connected by rods 29 to pins on the upper clamping members. Handles 31 are provided for turning the shafts 26 and their eccentrics, so that by this means the two pieces of felt are firmly clamped together while the needles are projected through the felt.

The cord *c* is placed in the groove 7 of the needles, as shown in Figs. 4 and 5, each needle being threaded in the same direction and in such a manner that when the needles are forced through the felt, a loop of the cord *c* is carried through the felt with each needle. After the needles are threaded, the parts of the machine are in the position shown in Fig. 3, the clamping members being raised.

The felt, which is passed through the saturating machine, is stopped when the end of the felt is in position above the splicing device. The end of the felt *a*, as shown in Fig. 5, is lapped over the end of another piece of felt *b*, the two felts having been passed through the space between the upper and lower clamping members so that the two sections of felt are directly above the needles. Then the needle carrier is raised by the lever 13 and the needles 6 puncture the felt and carry the loops of the cord *c* up through the perforations in the felt, as shown in Fig. 7. Then the draw wires 32, to which the cord *d* is attached, are passed through the notches 8 in the needles 6 and through the loops of the cord *c*, as shown in Figs. 6 and 7. The two cords *d*, after being drawn through, are tied to the cord *c* at each end, making a line of stitches throughout the width of the fabric and the needles are withdrawn. These stitches firmly splice the two ends of the felt together so that when the coating machine is set in motion one felt draws the felt of the other roll in through the space between the rolls of the coating or saturating machine.

In the present instance, after the splice has passed through the machine, the felt is cut at this point and the roll previously coat-

ed is removed from the machine and the new felt forms another roll.

I claim:

1. The combination in a machine for splicing felt and other fabrics, of two clamps spaced apart for holding two overlapping pieces of felt; a needle carrier having a series of needles, each needle having a slot in its end for the reception of a cord and also having a notch at the side for the reception of a tying cord; means for causing the needles to puncture the felt held between the clamps, the said needles carrying with them loops of one cord; and means for passing another cord through the notches in the needles and the loops so that, when the needles are withdrawn and the slack of the cord is taken up, the two pieces of felt are firmly secured together. 60 65 70

2. The combination in a machine for splicing two pieces of felt, or other fabric, of two clamps spaced apart; a needle carrier located between the clamps; two series of needles carried by the clamps; a bar above the needle carrier and having perforations 75 80 85 in line with the needles; means for raising the needle bar and forcing the needles through the felt, said needles being arranged to carry a loop of a cord through the perforations in the felt to form a loop; and means for passing a second cord through the loops of the first cord so that, when the needles are withdrawn and the clamps are released, the two pieces of material are 90 firmly secured together. 95

3. The combination in a machine for splicing felt and other fabrics, of two clamps spaced apart, each clamp consisting of a fixed member and a clamping member; an eccentric for operating the clamping member to clamp the two pieces of overlapping material; a perforated bar attached to the clamping members and movable therewith; a needle carrier located between the clamping members and having a row of needles thereon arranged to puncture the material held by the clamps; and means for raising and lowering the needle carrier, the needles having slots in the ends to receive a cord which is carried through the material with the needles to form loops and having a notch at the side for the passage of a draw wire and the cord to which it is attached. 100 105

RALPH G. JACKSON.
